CROSSBOW

Adolph V. Gruner, Pittsburgh, Pa.

Application January 25, 1949, Serial No. 72,669

2 Claims. (Cl. 124—25)

1

This invention relates to improvements in crossbows whereby greater accuracy of aim may be obtained than is ordinarily had in the use of this class of weapons.

One of the objects of the invention is to provide a novel construction of a bow and improved means for securing the same to the barrel of the crossbow.

Another object of the invention is to provide a novel means to prevent back-lash of the bow member after the projectile has been discharged.

Still another object of the invention is to provide novel means for tripping or releasing the bow-string without altering the tension of the bow-string when discharging a projectile.

The preferred embodiment of my invention is illustrated in the accompanying drawing, wherein:

Figure 1 is a perspective view of my improved cross-bar, showing the projectile in loaded position.

Figure 2 is a sectional view on line 2—2 in Figure 1.

Figure 3 is an isometric detail view of the bow securing means.

Figure 4 is a section on line 4—4 in Figure 1.

Figure 5 is a reduced fragmentary perspective view of the rigid strip and flexible bow, showing the notches which fit into the slots of the strip and bow securing means.

Figure 6 is a fragmentary perspective view showing in full lines the trigger details when in loaded position and in dot and dash lines, when in discharged position.

Figure 7 is a top view of the projectile or bolt as used in this invention.

Figure 8 is a sectional view showing the bow and damper in the saw cut of the barrel.

Similar numerals of reference indicate like parts throughout the several views in the drawing.

Referring now to the drawing, the particular construction of the crossbow 10 shown, comprises in general a barrel 11, a stock 12, the bow 13, a trigger mechanism 14 and the projectile or bolt 15.

The combined stock and barrel are preferably made of wood in which the latter is provided along its top edge 16 with a longitudinal groove or recess 17, extending from the muzzle 18 to a point 19 near the trigger mechanism 14. Groove 17 serves to guide the propelled projectile 15. The latter comprises a bullet-shaped body 20, terminating at the front into a pointed head 21 provided with a metallic point 22, and terminating at the rear into a tail 23, consisting of a pair

of spaced apart stiff feathers 24 in which the quills 25 are securely inserted. Feathers 24 are preferably arranged and spaced as shown in Figure 7, with the narrow barbs 26 opposing each other and the broad barbs 27 at the outside.

The top edge 16 of barrel 11, including the groove 17, terminates near the trigger mechanism 14 in the shape of a vertical shoulder 28 which is adapted to retain the bow-string 29 until released by trigger mechanism 14. The latter comprises a U-shaped trigger 30 pivotally mounted on a pivot pin 31 in a prepared cavity 32 at a point on the underside of the barrel near the trigger 30. A trigger pin 33, the lower end of which is secured to the bridge-portion of the U-shaped trigger 30, and the upper end of which is provided with a flat, square head 34, is vertically slidable in a vertical aperture 36. The shank 35 of trigger-pin 33 penetrates freely through the vertical aperture 36.

The trigger mechanism assumes a normal position, as shown in full lines in Figures 2 and 6, by gravity or by means of a coil spring 37, as shown.

25 The bow 13 is constructed of a single flat piece of flexible steel 38 backed up by a flat piece of stiff steel 39, both being secured to the barrel 11, near the muzzle 18, as follows: the flexible bow 13 and the stiff back-up strip or damper 39 are inserted in parallel relation in a prepared saw-cut 40 positioned adjacent the muzzle 18 at the underside of the barrel 11 (Fig. 8) after which slots 43 of the U-shaped bow and damper strip retainer 41 are slipped over both members 39 and 13 until the notches 42 of these members interlock with slots 43 of retainer 41. After the bow and damper are in position the retainer 41 is secured to the sides of the barrel 11 by screws 44, or otherwise.

30 The top of the saw-cut 40 is protected from 40 wear by means of a narrow metal strip 45 of the same width as the saw-cut which is bent over and forced into the sides of the barrel.

45 The string 29 is attached to the ends 47 of the flexible bow 13 in any suitable manner and when it is desired to operate the gun the projectile 15 is placed with its rear portion abutting pin 48 (Fig. 2) located near the trigger end of the groove 17 on the top edge 16 of barrel 11.

The trigger 30 is now in normal position (Figure 2) and the string 29 is placed around the shoulder 28, as best shown in Figures 1 and 2. The head 34 of trigger pin 33 is, normally, in a position as shown in Figure 2, either by gravity or by means of a coil spring 37. The stretched string 29 rests on top of head 34 and by pushing

trigger 30 upwardly, the top of head 34 of trigger pin 33 is also moved upwardly thereby causing string 29 to be slipped out of engagement with shoulder 28 over which the string has been stretched. The moment this occurs, the string violently strikes the rear end of the bullet shaped body 20 of the projectile 15, thereby causing the latter to be swiftly propelled forwardly from the bow.

In the crossbar structures of the prior art after the tensioned string has been slipped out of engagement with the shoulder 28 the string always passed over the muzzle 18 and below the barrel 11 instead of halting at the bow or only slightly in front of it as shown in dot and dash lines in Figure 1. This has been fully remedied by using a stiff back-up strip or damper 39 which lies in parallel alignment in saw-cut 40 with bow spring 38 and is held therein in the same manner as is the bow-spring. This arrangement prevents the ends of the bow-spring 38 from vibrating too far forwardly and at the same time prevents the string from passing the muzzle as it did before a damper strip 39 was applied.

It will thus be seen that I have provided an exceedingly simple, durable and highly efficient crossbow which assures almost perfect aim owing to the novel release of the string and other described features.

I claim:

1. In a crossbow, having a stock and a barrel with a projectile guiding slot therein, a bow member passing through the barrel at a point adjacent its muzzle and adapted, when relaxed, to lie in a plane perpendicular to the vertical plane of said barrel a separate damping member passing through the barrel in a plane parallel to the plane of the bow, said damping member being in contact with the bow at their mid-points only except when said bow is relaxed or forward of the relaxed position and adapted to dampen the forward movement of the bow when forward of its normally relaxed position, a U-shaped member fitted about the underside of the barrel and slotted to receive the bow and the damping member, a second U-shaped member passing through the barrel above the bow and damping member to protect the barrel from damage by the bow, a bow string connecting the ends of the bow, a vertical shoulder adjacent the junction of

5

barrel and stock receiving the bow string when the bow is drawn and releasing means adapted to release the bow string from said shoulder while maintaining substantially constant tension of the bow string until the instant of release.

2. In a crossbow, having a stock and barrel with a projectile guiding groove therein, a bow member passing through the barrel at a point adjacent its muzzle and adapted, when relaxed, to lie in a plane perpendicular to the vertical plane of said barrel and stock, a separate damping member passing through the barrel in a plane parallel to the plane of the bow, said damping member being in contact with the bow at their mid-points only except when said bow is relaxed or forward of the relaxed position and adapted to dampen the forward movement of the bow when forward of its normally relaxed position, a U-shaped member fitted about the underside of the barrel and slotted to receive the bow and damping member, a second U-shaped member passing through the barrel above the bow, a bow-string connecting the ends of the bow, a vertical shoulder adjacent the junction of barrel and stock receiving the bow-string when the bow is drawn and releasing means adapted to release the bow-string from said shoulder while maintaining substantially constant tension on the bow-string.

20

ADOLPH V. GRUNER.
